COMBINED DISPLAY AND CHARGING UNIT FOR BATTERY OPERATED TOOTHBRUSHES

Alfred W. Madl, Mequon, Wis., assignor to John Oster
Manufacturing Co., Milwaukee, Wis., a corporation of
Wisconsin

Filed Jan. 10, 1966, Ser. No. 541

Term of patent 14 years

(Cl. D4—3)

Fig. 1.

Fig. 2.

FIG. 1 is a front perspective view of a combined display and charging unit for battery operated toothbrushes embodying my new design;

FIG. 2 is a side elevational view thereof;

FIG. 3 is a top plan view thereof;

FIG. 4 is a rear elevational view thereof; and

FIG. 5 is a top plan view thereof as viewed in FIG. 3 with the transparent cover portion removed.

The elements shown in broken lines in FIG. 1 are included for illustrative purposes only.

I claim:

The ornamental design for a combined display and charging unit for battery operated toothbrushes as shown and described.
